UNITED STATES PATENT OFFICE.

WILLIAM S. BIEL, OF LOS ANGELES, CALIFORNIA.

DESIGN FOR A BEDSTEAD.

14,566.

Specification of Reissued Design. Reissued Dec. 17, 1918.

Original No. 49,793, dated October 24, 1916, Serial No. 110,603, filed July 21, 1916, for 3½ years. Application for reissue filed August 5, 1918. Serial No. 248,480. Term of patent 14 years.

To all whom it may concern:

Be it known that I, WILLIAM S. BIEL, a citizen of the United States, residing at Los Angeles, in the county of Los Angeles and State of California, have invented a new, original, and ornamental Design for Bedsteads, of which the following is a specification, reference being had to the accompanying drawing, forming a part thereof.

The figure is a perspective view of a bedstead showing my new design.

I claim:

The new and ornamental design for a bedstead, as shown.

WILLIAM S. BIEL.
